UNITED STATES PATENT OFFICE.

HORACE WYMAN, OF WORCESTER, MASSACHUSETTS, ASSIGNOR TO THE CROMPTON LOOM WORKS, OF SAME PLACE.

JACQUARD MECHANISM FOR LOOMS.

SPECIFICATION forming part of Letters Patent No. 391,730, dated October 23, 1888.

Application filed April 21, 1888. Serial No. 271,427. (No model.)

To all whom it may concern:

Be it known that I, HORACE WYMAN, of Worcester, county of Worcester, and State of Massachusetts, have invented an Improvement in Jacquard Mechanisms for Looms, of which the following description, in connection with the accompanying drawings, is a specification, like letters on the drawings representing like parts.

10 The jacquard to be herein described contains double-ended needles, with which co-operate two sets of Jacquard cards, according to the pattern to be woven, each set of cards controlling its own pattern, one serving in the 15 production of, say, the body of a fabric, while the other serves for a stripe or border.

In accordance with my invention the double-ended needles have long eyes, which receive through them stop-pins forming parts of 20 holder-bars, while the ends of the needles, after passing through spiral springs, are extended through holes in guide-bars, the change of positions of the guide-bars and holder-bar acting to compress the said springs and place one or 25 the other end of the eye of the needle against the stop-pins, according to which end of the needle is to be acted upon by the Jacquard card, as will be described.

Figure 1 is a top or plan view of a Jacquard 30 attachment embodying my invention, the top boards and lifting-boards being partially broken away to show parts under them, the Jacquard cylinder at the right being operative; Fig. 2, a section of Fig. 1 in the dotted line *x*; Fig. 3, a detail in plan of part of the devices 35 for moving the Jacquard cylinders; Fig. 4, a broken detail view taken from the right of Fig. 2; Fig. 5, a detail view showing three needles and their supporting guide-bars and 40 holding-bar, the parts being in position to make the right-hand end of the needles operative, one of the needles being shown as pushed to the right, as it would be by the card of the right hand cylinder. Fig. 6 is a vertical section taken through the guides and 45 holder, showing the needles as arranged in their vertical rows. Fig. 7 is a view similar to Fig. 5, but with the guide-bars and holder-bar changed in position to enable the left-hand

ends of the needles to be operative; Fig. 8, a 50 modification to be referred to, and Fig. 9 yet another modification.

In my invention I shall not show the harnesses and the operative parts of the loom, as they may be of any usual or suitable construction. 55 Neither is it deemed necessary to show devices for moving the lifting-boards, as they may be of any usual construction. I have also omitted from the cylinders the Jacquard cards, and in the cylinders I have made but two rows 60 of holes, as I have shown but two rows of needles.

The frame-work A, the top board or boards, A', the lifting board or boards A², the guide-bars A³ A⁴, the knot-cords *a*, or harness-lifters, having the knots 2, carrying the harnesses, and the Jacquard cylinders *a'* *a''*, are and may be of usual construction, the cylinders in practice having a series of holes—one for each needle—and carrying a series of 70 Jacquard cards, all as usual. The cylinder *a'* has its journals in a frame consisting of two like levers or arms *a'*, pivoted at *a'*, and having pins or projections, as *a'*, which enter slots in like links, *a'*, jointed at *a'* to like arms, *a'*, of a 75 rock-shaft, *a'*, having an arm, *a'*, to which is jointed a connecting-rod, *a'*, extended down to a cam or other shaft of the loom, where it is operated at the proper times—as, for instance, in United States Patent No. 2,625, May 16, 80 1842, or in any other usual manner. The arm *a'* has a projection, 3, which at times acts against a stud or projection, 4, of an elbow-lever, *b*, pivoted at *b'*, two such elbow-levers constituting the frame carrying the cylinder *a'*. 85

The two frames carrying the two cylinders *a'* *a''* are connected together or normally drawn toward the center of the Jacquard head by springs *b*. The needles *n*, composed of wire, are bent to form eyes 45 for the reception of 90 the knot-cords, which are connected in usual manner to the harnesses, and to form stop-eyes 6, which, passing between the pins 24, serve to hold the eyes 45 in a horizontal position, and also through which are extended the 95 stop-wires 7, inserted through a holder-frame, *c*.

Each needle is provided with two springs, as 14 and 15, one near each end thereof, the

said springs being herein shown as placed between a shoulder or projection of the needle and the guide-bars 12 and 13.

The guide-bars 12 13 form part of a sliding frame, the side pieces of which are marked *d*, and which are free to slide in guides 16, secured to the frame-work A. The guides 16 also receive in them loosely the arresting or stop bar *e*, bent at its ends, as shown in Fig. 1, and adapted to be placed in line with one or the other of the two frames carrying the Jacquard cylinders *a' a²*, to hold one of the said frames from moving inwardly sufficient to strike and move the needles. This bar *e* has secured to it one end of the holding-bar *c*, the opposite end of the said bar being fast to a rod, *c'*, free to slide in suitable guides, *c²*. The head has in it a rock-shaft, *f*, having a handle, *f'*, the rock-shaft near each bar *d* being provided with two arms, as 20 21, to which are jointed, respectively, the links 22 23, joined, respectively, to the rods *d* and to the bars *e' e²*, the partial rotation of the shaft *f* in one or the other direction moving the guide-bars 12 13 in one and the holder-bar *c* in the other direction, thus compressing one or the other of the set of springs 14 or 15.

When the guide-bars 12 13 are moved to the right, as in Fig. 5, and the holding-bar to the left, the stops 7 come into the left-hand end of the stop-eyes 6 and the springs 7 are compressed, and in such condition the right-hand ends of the needles *n* are in condition to be acted upon by the usual Jacquard cards carried by the cylinder *a'*.

Fig. 5 shows one of the needles pushed back as it will be when struck by a Jacquard card.

Fig. 7 shows the guide-bars 12 13 and the holder-bar *c* in reverse positions from that in Fig. 5, and in Fig. 7 the left-hand ends of the needles are in condition to be acted upon by the usual cards on the cylinder *a²*, the stops 7 being in the right-hand ends of the stop-eyes 6, the springs 14 being compressed.

The different vertical rows of needles are separated by division-rods or guide-pins 24. (Shown only in Figs. 5, 6, and 7.) The handle or lever *f'* has connected to it a link, 25, which in practice may be attached to a lever to be moved by a cam or by the operator whenever it is desired to change from one to the other position.

When the cylinder *a'* is operative, the bar *e* acts to hold the frame carrying the cylinder *a²* back from the ends of the needles *n*, as shown best in Fig. 2, at which time the arm *a¹²* in its vibrations does not have to meet and turn the frame *b*, the pin *a⁵* at such time being kept in the inner end of the slot in the link *a⁶* by the spring *b²*; but when the frame *a³* of the cylinder *a'* is held back by the bar *e*, as it will be when the parts are as in Fig. 7, then the ear 3 of the arm *a¹²* will move the elbow-lever *b*, and the slot in the end of the link *a⁶* enables it to move on the pin *a⁵* and not turn the lever *a³*.

The knot or lifting-boards will have holes with slots at one side, as in Fig. 1, the cords *a*

being lifted whenever moved into the narrow parts of the slots. The same devices operate both of the frames carrying the cylinders.

Instead of employing harness-lifters composed of cords having knots, the needles *n* may be used to shift harness-lifters, (shown in Fig. 8 as hooks *D*,) which will be engaged by "griffes," as in United States Patent No. 185,027, December 5, 1876.

I do not desire to limit my invention to the employment of the needles and cylinders herein described to that class only of jacquard in which the lifting-boards are divided and are actuated in opposed directions simultaneously, for my invention as herein claimed may be applied with equal facility to that class of jacquards wherein a single lifting-board or equivalent is moved up and down.

I denominate as "harness-lifters" not only the cords *a*, but any usual equivalent controlled by the needles and joined to the harnesses or heddles carrying the warps.

The needles may have only one eye instead of two, and the eye may be shaped as at 4^X, Fig. 9.

I claim—

1. In a jacquard, the following instrumentalities, viz: a set of double-ended needles having eyes to control the harness-lifters, and stop-eyes 6, and two springs surrounding each needle to move it, when desired, in either direction, combined with two guide-bars and an intermediate holder-bar and stops, and means to move the guide-bars and the holder-bar, and with two Jacquard cylinders, one of which may be used to act on one or the other end of the said sets of needles at the will of the operator, substantially as described.

2. The double-ended needles, their guide-bars, holder bar, springs, stops, and bar *e*, and two Jacquard cylinders and their carrying levers or frames, combined with means to move the said levers or frames, whereby they may be moved except when held out of operative position by the said bar *e*, and with means to move the guide-bars and holder-bar and the bar *e*, substantially as described.

3. In a jacquard, the two cylinders *a' a²*, needles and guides therefor, the carrying-frames for the said cylinders, and the rock-shaft *a¹⁰* and its attached arms *a¹² a⁹*, and link *a⁶*, combined and operating substantially as shown and described.

4. The needles *n*, having eyes 4 and stop-eyes 6, and the two sets of springs to move the needles in either direction, the guide-bars 12 13 for the said needles, the holder-bar, and stops to engage the stop-eyes, combined with means to actuate the said guide-bars and stop-eyes, substantially as described.

In testimony whereof I have signed my name to this specification in the presence of two subscribing witnesses.

HORACE WYMAN.
